DEEP WELL PUMP

Filed Oct. 27, 1943

UNITED STATES PATENT OFFICE

2,384,173

DEEP WELL PUMP

Douglas Johnston, Shelbyville, Ill.

Application October 27, 1943, Serial No. 507,816

11 Claims. (Cl. 103—46)

The present invention relates to a deep well pump.

It is an object of the invention to provide a pump in which the string to contain the column of fluid being pumped, and a single relatively small pressure line, comprise all of the mechanism necessary to be strung down the well casing, between the mouth of the well and the pump mechanism per se.

A further object of the invention is to provide a pump of this kind, wherein the actuation of a remote pumping device is controlled by a fluid displacing mechanism at the surface, acting upon the column of pumped fluid. A further object is to provide a simple pumping mechanism, adapted to be located at the bottom of a well, urged in one direction by fluid under pressure, preferably air at constant pressure, and alternately actuated in the other direction against the column of fluid by selective pressures applied at the top of the well against the column of liquid being pumped.

In the drawing:

Fig. 1 is a side elevation of the device partly broken away;

Fig. 2 is a vertical medial section of the pumping mechanism per se;

Fig. 3 is a sectional view of a modified type of pump.

In the drawing, a well casing 10 is disposed in the usual manner in a well, which may be an oil well or a water well, or the like. The ensuing description will be made in connection with a deep oil well, although clearly the pump is applicable to any like fluid at any depth. The casing 10 has a head 11 secured thereto. A well string 12 extends through the head 11 and connects with a T 13. This T receives a connection 14, through which extends a high pressure air line 15 that extends down through the well string 12. The other branch of the T 13 extends into a displacing mechanism, generally indicated at 16.

The well string 12, made up of the necessary number of units, depending upon the depth of the well, is connected at its bottom to a pump housing 18. This, in turn, at its lower end, is connected by a connector 19 to a smaller secondary pump housing 20 that fits into the liquid-containing zone of the well through the medium of a tip 21 connected thereto by a valve containing union 22. The tip 21 has the usual ports 23 through which the liquid being pumped may flow.

The upper pump housing contains a sleeve or cylinder 25 attached to the upper edge of the connector 19. This provides an annular space be-

tween the housing and the cylinder 25, indicated at a. The cylinder 25 is sealed at its upper end at 26 and receives the end of the pressure tube 15, which thereby opens into the upper end of the cylinder.

The sleeve likewise contains a reciprocable piston 27 secured to a piston rod 28 that extends through the connector 19 into the secondary pump housing 20. At its lower end the piston rod 28 is secured to a ported member 29 that, in turn, is attached to a second piston 30. The piston 30 is provided with an axial bore 31, the upper end of which flares to provide a valve seat against which a ball valve 32 may seat in sealing relation to prevent the flow of liquid downward through the ported member 29 into the passage 31. The area between the pistons 27 and 30, and bounded by the cylinders 25 and 20, is designated as pumping chamber c.

The connector member 22 at the bottom of the secondary pump housing 20 has a valve seat sleeve 33 that receives a ball valve 34 that seats thereon to prevent the flow of liquid downwardly from the housing 20 into the tip 21. The space beneath the piston 27 and above the valve 34, is designated as intake chamber d.

The cylinder 25 has ports 36 that provide communication between the pumping chamber c and the area a.

A check valve port 37 leads from the pumping chamber c past a ball check valve 38 into the space a.

A float valve 40 at the top of the pump mechanism, within the compression chamber b, is operated by a float 41 pivoted at 42 to the cap 26. The valve 40 controls an outlet line 43 that extends within the pump housing 18 and communicates through a port 44 with the interior of the well casing 10 outside of the secondary pump housing or cylinder 20.

The displacing mechanism 16 includes a valve housing generally indicated at 47. This valve housing has a central cylindrical bore 48 therein. This bore 48 terminates at one end in an inlet 49, somewhat smaller than the bore to provide a shoulder between them. The bore 48 opens through the housing wall at the opposite end. An insert 50 is secured in the end of the bore 48, and has a projection thereon for a purpose to be described.

A hollow extension 51, the interior of which is in communication with the bore 48, is secured to the housing 47. The extension has a head and a packing gland, through which a displacement

plunger 52 reciprocates. A power driven arm 53 is secured to the plunger 52 to reciprocate it.

Within the bore 48 slides a valve block 54, moving between the shoulder, between the bore and the inlet 49, and the projection on the insert 50. The space within the bore 48 and the extension 51 to the right of the valve 54 is designated as the displacement chamber, indicated by 55.

The valve housing 47 contains a compression by-pass 56 that connects the displacement chamber 55 with the outlet 49. This port opens into the bore 48 immediately to the right of the valve block 54 when it is in its left position. The compression port is controlled by a ball check valve 57 that permits flow from the compression chamber 55 to the outlet 49, but prevents flow in the reverse direction.

The valve housing 47 also contains a principal outlet 58, that opens into the bore 39 to the left of the compression by-pass. This outlet is closed by the valve 54 in the position of the drawing. As the valve moves to the right, it first closes the by-pass 56, and then opens the outlet 58 to communication with the inlet 49. The sequence is the reverse of this when the valve 54 moves to the left.

The valve housing 47 further contains a refilling port 59 that connects the outlet 58 with the displacement chamber 48, connecting into the latter at a point to the right of the valve 54 when the latter is in its right position. This refilling port 59 is controlled by a ball check valve 60 that permits flow from the outlet 58 to the displacement chamber 55, but prevents reverse flow.

The outlet 58 may be connected to whatever is to receive the oil, such as a reservoir.

Operation

With the string disposed in the casing 10 so that the tip extends into the oil containing part of the well, an oil level may build up within the casing to some point such as L. The line 15 is connected to a source of high pressure air. This pressure must be greater than the unit pressure exerted by a column of oil acting within the pump string. The connecting device is started by operating the rod 53 in and out of the displacement chamber 55 by suitable motor.

The string 12, the pump housing 18, and the pumping chamber c will be filled with oil. The displacement chamber 55 is also filled with oil, with the plunger 52 withdrawn. The foregoing oil, at the start, may be filled into these parts, or may flow back from the reservoir into them. Flow back is always permitted when the valve 54 is in either extreme position, as the port 58 may be directly connected to the inlet 49, or may be indirectly connected through the ports 59 and 56. After the pump has been in operation, these parts will be kept filled automatically.

The plunger 52, moving into the oil in the displacement chamber 55, forces displacement thereof. As the check valve 60 closes the port 59, the pressure added by the plunger 52 causes the valve 54 to move to the left. This first cuts off the outlet 58, then opens the by-pass 56, permitting the oil to be forced past the check valve and into the string 12, the chamber a, and the pumping chamber c.

The condition when the mechanism is in the position of Fig. 1, therefore, is that pressure within the pump at the bottom of the well consists of air pressure acting to lower the piston 27, the previously described pressure of the column of oil acting within the pumping chamber c differen-

tially beneath the piston 27 and above the piston 30 to produce an upward force on both pistons, owing to the greater size of the piston 27. The resultant upward oil pressure acting in the pumping chamber c is greater than the air pressure acting downwardly in the compression chamber b, so that both pistons are raised. As a result of the foregoing, the mechanism, as shown in Fig. 1, has the pistons in their upper positions with a high oil pressure acting throughout the string. This high pressure acts upon both ends of the valve block 54.

The ascent of the lower piston 30 produces a low pressure within the intake chamber d, and oil is drawn in through the tip ports 23, past the check valve 34, into the chamber. The oil at high pressure above the piston 30 is prevented from escape to beneath the piston by the check valve 32.

When the plunger 52 is withdrawn, or is relieved of its force displacing it inwardly, the pressure within the displacement chamber 55 is lowered. The check valve 57 prevents escape of oil from the string with the valve block 54 to the left, so that the high pressure continues to act upon the left end of the valve block. As noted hereafter, this force may include a component due to swelling of the tubes.

This reduction of pressure on the right end of the valve block 54, accompanied by maintenance of pressure on the left end thereof, causes the valve block 54 to be moved to the right. This first cuts off the port 56, and thereafter opens the outlet port 58, the valve block coming to rest against the extension on the insert 50, so that the port 59 is held open. When the port 58 is opened, the high pressure on the oil column is relieved, and becomes lower than the constant pressure acting upon the top of the piston 27 and produced by the air. Thereupon, the piston 27 is forced down, carrying with it the piston 30. As the piston 30 moves down, the oil in the intake chamber d is forced through the port 31, past the check valve 32 and into the pumping chamber c. This oil constitutes the new charge of oil introduced on each pump stroke. It may be assumed that the piston 30, in effect, merely moves through oil, so that its descent does not substantially enlarge the capacity of its pumping chamber c. Hence the pumping chamber is greatly reduced in size by the descent of the piston 27, forcing oil out through the ports 36 from the pumping chamber c into the space a and the string. This oil finally finds its way through the valve mechanism 16 into the outlet 58.

Upon the next inward stroke of the plunger 52, the valve 54 is shifted, and oil is again forced into the pumping chamber c, lifting the piston. However, the new charge of oil, previously entrapped above the piston 30, also contributes to the oil in the pumping chamber. The result is that on each downward stroke of the piston 27 an amount of oil is forced out of the chamber c equal to the sum of the amount added by the plunger 52 and that entrapped by the piston 30. The net gain per stroke is the amount of oil entrapped by the piston 30.

It will be seen that the displacement chamber may always be refilled through the port 59, from the outlet 58. When the plunger 52 is withdrawn, it will draw refilling oil past the check valve 60. During the displacement of the valve 54 on compression stroke, it closes the outlet port 58 before opening the by-pass 56, thus preventing relief of the compression pressure through the outlet. Upon reverse movement, the valve 54 closes the

by-pass before opening the outlet, thus preventing loss of high pressure before the valve has completely shifted, and assuring refilling of the entire valve mechanism, for a subsequent stroke. Further, if the pressures employed cause swelling of the tubing, the first result of rightward displacement of the valve 54 will be to relieve this pressure in the tubes, permitting them to contract to normal position. Preferably the space between the left end of the valve 54 in leftmost position, and that end when it opens the outlet 58, is sufficiently large to absorb the oil displaced thus by the contracting tubes. Therefore, the oil ejected upon opening of the outlet 58 will not spurt out at high velocity, but will flow at the velocity determined by the air pressure. By this means the force of the contracting of the tubing will move the valve 54 rapidly enough to maintain a relatively high pressure in the displacement chamber 55, accelerating the plunger 52 on the return or withdrawal stroke, and providing energy that may be stored in a flywheel for a subsequent displacement stroke.

The check valve 38 acts to permit the oil under pressure in the string to enter the pumping chamber ²⁵ c to lift the piston 27, even if the piston moves down so that it closes off the ports 36. Further, as the piston 27 descends and closes off the ports 36, the gradual constriction of these ports decelerates the piston so as to prevent too great an impact thereof against the elements limiting the descent. The presence of the check valve 38 prevents escape of this resisting pressure, while permitting the reverse flow as above.

The float valve 40 is opened by any oil that may leak past the piston 27 as soon as such oil reaches a critical level. It is thus prevented from passing up the air line 15, or from restricting upward movement of the piston which might cause destruction of parts, owing to the incompatibility of the liquid being pumped.

The air pressure may desirably be about 10% above the normal hydrostatic pressure of the oil acting within the pumping chamber c. The compression chamber b is preferably made large enough to prevent pressure fluctuations of more than 3% when the piston 27 moves from one extreme to the other.

In some installations, a spring may be employed in place of air pressure. This is particularly true in shallower pumps, such as home well pumps. Such a modification is shown in Fig. 3, wherein the housing 18, the cylinder 25, the cap 26, and the piston 27 appear as before. However, a spring 65 is employed between the cap 26 and the piston 27 to apply the fixed force greater than that due to the hydrostatic pressure opposing the piston 27, but less than the total pressure built up when the plunger 52 is driven inwardly. A drain tube 86 connects through the cap 26 to open to atmospheric pressure in the casing above the fluid level and prevents building up of excess pressure within the spring chamber. It also will carry off excess liquid that leaks past the piston 27.

What is claimed is:

1. An apparatus for pumping liquid from a supply against the pressure of a column of the liquid being pumped, comprising a pair of adjacent, differently-sized cylinders at the bottom of the column, a piston in each cylinder, the pistons being connected for movement together, the cylinders and pistons forming a pumping chamber between them, a constant pressure means acting on the pistons to drive them in one direction ⁷⁰ 75

to reduce the size of the pumping chamber, an outlet between the pumping chamber and the column, to introduce column pressure to urge the pistons against the constant pressure, the column pressure producing greater force upon the large piston than the small one, valve means associated with the smaller piston to provide an intake chamber, said valve means being check valves to entrap liquid from the supply into the intake chamber upon movement of the pistons by the column pressure, and to expel the entrapped liquid into the pumping chamber upon movement of the pistons by the constant pressure, whereby the cycling of the pistons introduces a new charge of liquid into the pumping chamber each cycle and pumps an equivalent amount into the column, a check valve controlled passage between the pumping chamber and column connecting beneath the larger piston in its lowest position, and preventing flow from the pumping chamber and the column, means to effect said cycling of the pistons, comprising means to isolate the column, means to increase the pressure thereof to produce a force on the larger piston greater than that of the constant pressure, and to release said pressure and free the column from isolation whereby the constant pressure may pump the liquid of the column.

2. A pumping apparatus for lifting liquid from a supply against the pressure of the column being lifted, including a pumping mechanism located at the bottom of the column, having pumping means actuated by increase and decrease of the pressures of the column of the liquid, above and below an opposing pressure, and means locatable above the bottom of the column for effecting increase and decrease of column pressures, comprising a valve housing with an inlet connecting into the column, an outlet from the housing, a valve member, a displacement chamber in communication with the liquid column, and a displacement member movable in to and out of the displacement chamber to change the size thereof, means admitting liquid to the displacement chamber, said displacement member, upon movement into the chamber, being adapted to operate the valve to cut the outlet off from the inlet, and to apply a pressure to the liquid in the column to actuate the pumping mechanism.

3. A pumping apparatus for lifting liquid from a supply against the pressure of the column being lifted, including a pumping mechanism located at the bottom of the column, having pumping means actuated by increase and decrease of the pressures of the column of the liquid, above and below an opposing pressure, and means locatable above the bottom of the column for effecting increase and decrease of column pressures, comprising a valve housing with an inlet connecting into the column, an outlet from the housing, a valve member, a displacement chamber, a displacement member movable inwardly and outwardly of the chamber to vary the size thereof, a passage adapted to connect the chamber and the liquid column, the valve being movable from a first position in which the inlet and outlet are in communication with the passage cut off, to a second position wherein the outlet is cut off and the inlet and passage are in communication, the valve being adapted to be moved from its first to its second position when the displacement member is moved inward.

4. A pumping apparatus for lifting liquid from a supply against the pressure of the column being lifted, including a pumping mechanism located at the bottom of the column, having pumping means

actuated by increase and decrease of the pressures of the column of the liquid, above and below an opposing pressure, and means locatable above the bottom of the column for effecting increase and decrease of column pressures, comprising a valve housing with an inlet connecting into the column, an outlet from the housing, a valve member, a displacement chamber, a displacement member movable inwardly and outwardly of the chamber to vary the size thereof, a passage adapted to connect the chamber and the liquid column, the valve being movable from a first position in which the inlet and outlet are in communication with the passage cut off, to a second position wherein the outlet is cut off and the inlet and passage are in communication, the valve having a surface exposed to column pressure and an opposite surface exposed to displacement chamber pressure, and a check valve in the passage preventing flow from the column through the passage, the valve being adapted to be moved from its first position toward its second upon inward movement of the displacement member, and the outlet and passage being disposed so that the outlet is cut off before the passage is opened.

5. A pumping apparatus for lifting liquid from a supply against the pressure of the column being lifted, including a pumping mechanism located at the bottom of the column, having pumping means actuated by increase and decrease of the pressures of the column of the liquid, above and below an opposing pressure, and means locatable above the bottom of the column for effecting increase and decrease of column pressures, comprising a valve housing with an inlet connecting into the column, an outlet from the housing, a valve member, a displacement chamber, a displacement member movable inwardly and outwardly of the chamber to vary the size thereof, a passage adapted to connect the chamber and the liquid column, the valve being movable from a first position in which the inlet and outlet are in communication with the passage cut off, to a second position wherein the outlet is cut off and the inlet and passage are in communication, the valve having a surface exposed to column pressure and an opposite surface exposed to displacement chamber pressure, and a check valve in the passage preventing flow from the column through the passage, the valve being adapted to be moved from its first position toward its second upon inward movement of the displacement member, and the outlet and passage being disposed so that the outlet is cut off before the passage is opened, a second passage between the outlet and the displacement chamber, and a check valve therein to prevent flow of liquid from the displacement chamber to the outlet.

6. A pumping apparatus for lifting liquid from a supply against the pressure of the column being lifted, including a pumping mechanism located at the bottom of the column, having pumping means actuated by increase and decrease of the pressures of the column of the liquid, above and below an opposing pressure, and means locatable above the bottom of the column for effecting increase and decrease of column pressures, comprising a valve housing with an inlet connecting into the column, an outlet from the housing, a valve member, a displacement chamber, a displacement member movable inwardly and outwardly of the chamber to vary the size thereof, a passage adapted to connect the chamber and the liquid column, the valve being movable from a first position in which the inlet and outlet are in communication with the passage

5 cut off, to a second position wherein the outlet is cut off and the inlet and passage are in communication, the valve having a surface exposed to column pressure and an opposite surface exposed to displacement chamber pressure, and a check valve in the passage preventing flow from the column through the passage, the valve being adapted to be moved from its first position toward its second upon inward movement of the displacement member, and the outlet and passage being disposed so that the outlet is cut off before the passage is opened, the distance the valve must move from second position before opening the outlet being sufficient to reduce, at least substantially, the pressure of swelling of the parts containing the liquid under pressure.

7. In a pumping mechanism for raising a column of liquid from a supply, differently-sized cylinders, interconnected pistons in the cylinders, said cylinders and pistons forming a pumping chamber between the pistons, means establishing a substantially constant pressure action to move the pistons in one direction, an outlet for connecting the pumping chamber with the column, means to increase and decrease the pressure on the column of liquid in such manner as to cause the pistons to be reciprocated, means for placing a new charge of liquid in the chamber from the supply upon each cycle of movement of the pistons, and means for returning to the supply liquid which may leak past the larger piston from the pumping chamber.

8. In a pumping mechanism for raising a column of liquid from a supply, differently-sized cylinders, interconnected pistons in the cylinders, said cylinders and pistons forming a pumping chamber between the pistons, means establishing a substantially constant pressure action on one of the pistons to move the pistons in one direction, an outlet for connecting the pumping chamber with the column, means to increase and decrease the pressure on the column of liquid in such manner as to cause the pistons to be reciprocated, means for placing a new charge of liquid in the chamber from the supply upon each cycle of movement of the pistons, and means preventing the entrapment of liquid in the cylinder at that side of the larger piston opposite the pumping chamber in the event of leakage past said piston from the pumping chamber.

9. In a pumping mechanism for raising a column of liquid from a supply, differently-sized cylinders, interconnected pistons in the cylinders, said cylinders and pistons forming a pumping chamber between the pistons, means for maintaining a substantially constant pneumatic pressure in the larger cylinder behind the larger piston so as to be effective on said piston to move both pistons in one direction, an outlet for connecting the pumping chamber with the column, means to increase and decrease the pressure in the column of liquid in such manner as to cause the pistons to be reciprocated, means for placing a new charge of liquid into the chamber from the supply upon each cycle of movement of the pistons, means for placing the portion of the larger cylinder behind the piston therein in communication with the supply, and valve means for controlling said communication so as to permit liquid which leaks past the larger piston to return to supply, said last-named valve means including a float for moving the valve to open position.

10. In an apparatus for operating a sub-surface pumping mechanism located at the bottom

of a column of liquid to be lifted and having pumping means actuated by increase and decrease of the pressures of said column of liquid, a housing member having a displacement chamber connected to the column, a displacement member movable into and out of said chamber, an outlet from the housing providing a pressure relieving liquid discharge means, and valve means for controlling the outlet, said valve means being arranged to be maintained closed during operation of the displacement member into the chamber and to be opened during operation of the displacement member out of the chamber.

11. In an apparatus for operating a sub-surface pumping mechanism located at the bottom of a column of liquid to be lifted and having pumping means actuated by increase and de-

crease of the pressures of the column, a housing member having a displacement chamber connected to the column, a displaceable member movable into and out of the chamber to vary the volume thereof, an outlet providing a pressure relieving and liquid discharge means, valve means for controlling the outlet and arranged to be maintained closed when the displacement member is moved inwardly to decrease the volume of the chamber and apply pressure to the liquid column and to be open when the displacement member is moved outwardly to increase the volume of the chamber, and means admitting liquid to the chamber during the outward movement of the member.

DOUGLAS JOHNSTON.
